US0D1082826S

(12) **United States Design Patent** (10) **Patent No.:** **US D1,082,826 S**
Penacho et al. (45) **Date of Patent:** **** Jul. 8, 2025**

(54) **DISPLAY SCREEN OR PORTION THEREOF WITH A GRAPHICAL USER INTERFACE**

(71) Applicant: **Aristocrat Technologies Australia Pty Limited**, North Ryde (AU)

(72) Inventors: **Gary Penacho**, Henderson, NV (US); **Patrick Finch**, Las Vegas, NV (US)

(73) Assignee: **Aristocrat Technologies Australia Pty Limited**, North Ryde (AU)

(**) Term: **15 Years**

(21) Appl. No.: **29/914,873**

(22) Filed: **Oct. 23, 2023**

(57) **CLAIM**

The ornamental design for a display screen or portion thereof with a graphical user interface, as shown and described.

DESCRIPTION

FIG. 1 is a front view of a first embodiment of a display screen or portion thereof with a graphical user interface showing the new design;

FIG. 2 is a front view of a second embodiment of a display screen or portion thereof with a graphical user interface showing the new design;

FIG. 3 is a front view of a third embodiment of a display screen or portion thereof with a graphical user interface showing the new design; and,

FIG. 4 is a front view of a fourth embodiment of a display screen or portion thereof with a graphical user interface showing the new design.

The outermost broken line illustrates a display screen or portion thereof and forms no part of the claimed design. The remaining broken lines represent elements of the display screen or portion thereof with a graphical user interface that form no part of the claimed design.

1 Claim, 4 Drawing Sheets

Related U.S. Application Data

continuation of application No. 29/615,031, filed on Aug. 25, 2017, now Pat. No. Des. 852,830.
